SWITCHING APPARATUS

Bernard D. Willis, Oak Park, Ill., assignor to
Automatic Electric Laboratories, Inc., a corpora-
tion of Delaware

Application October 1, 1941, Serial No. 413,176

7 Claims. (Cl. 177—353)

The present invention relates to switching apparatus and more particularly to improved automatic switching apparatus for automatic telephone systems of the character of that disclosed in U. S. Patent No. 2,222,131, Bernard D. Willis, granted November 19, 1940.

In a conventional automatic telephone system, the automatic switching apparatus is selectively controlled in accordance with different digits comprising corresponding different numbers of impulses. However, in an automatic telephone system of the character of that disclosed in the Willis patent mentioned, the automatic switching apparatus is selectively controlled in accordance with different digits in the form of a single impulse and comprising corresponding different time durations. More particularly, in automatic switching apparatus of the type mentioned, the wiper is advanced continuously with respect to the contacts in the associated contact field accessible thereto during the time duration of the impulse.

While an automatic telephone system utilizing automatic switching apparatus of the type mentioned is entirely satisfactory in operation, nice adjustment of the timing mechanism incorporated in the call transmitter disposed at each telephone station in the system is required in order to obtain proper control of the automatic switching apparatus from the telephone station; otherwise the wiper in the automatic switching apparatus may not be precisely centered with respect to the selected contact in the associated contact field when the selecting advancement of the wiper is arrested.

Accordingly, the principal object of the present invention is to provide in automatic switching apparatus of the type mentioned, mechanism for positively centering the wiper thereof with respect to the contact last engaged thereby in the associated contact field after the selecting advancement of the wiper has been arrested.

Another object of the invention is to provide in automatic switching apparatus of the type mentioned, mechanism for releasing the automatic switching apparatus in response to the selecting advancement of the wiper thereof beyond the last contact in the associated contact field.

A further object of the invention is to provide automatic switching apparatus of the type mentioned which is of improved and simplified construction and arrangement.

A still further object of the invention is to provide automatic switching apparatus of the

type mentioned including an improved and simplified circuit arrangement for selectively controlling the operation thereof.

The invention, both as to its organization and method of operation, together with further objects and advantages thereof, will best be understood by reference to the following specification taken in connection with the accompanying drawings, in which Figure 1 is a fragmentary front elevational view of switching mechanism embodying the present invention; Fig. 2 is a fragmentary side elevational view of the switching mechanism shown in Fig. 1; Fig. 3 is a fragmentary plan view of a portion of the switching mechanism shown in Figs. 1 and 2; Fig. 4 is a fragmentary side elevational view of a modified form of the switching mechanism; Fig. 5 is a fragmentary front elevational view of the switching mechanism shown in Fig. 4; and Fig. 6 illustrates diagrammatically an automatic telephone system embodying the present invention and incorporating switching mechanism of either the form shown in Figs. 1 to 3, inclusive, or the form shown in Figs. 4 and 5.

Referring now more particularly to Figs. 1 to 3, inclusive, of the drawings, there is illustrated switching mechanism 10 embodying the present invention and comprising a wiper set 11 and an associated contact bank 12, the contact bank 12 including an insulating structure 13 supporting a plurality of vertically spaced-apart contact sets 14 arranged in a row. Also, the mechanism 10 comprises a rotatably mounted shaft 15 having a cam 16 rigidly secured thereto, the cam 16 having the general configuration of an involute and comprising first and second laterally spaced-apart cam surfaces 17 and 18. The first cam surface 17 has a plurality of spaced-apart involuted teeth 19 disposed about the periphery thereof; while the second cam surface 18 has a smooth peripheral face. The cam 16 is biased in the counterclockwise direction into a normal position, illustrated in Fig. 1, by an arrangement comprising a surrounding coil spring 20, one end of the coil spring 20 being secured to the shaft 15 and the other end of the coil spring 20 being secured to an externally supported pin 21. Also the mechanism 10 comprises a follower 22 which is mounted by two brackets 23 and 24 for pivotal movement, the bracket 23 being externally supported by an arrangement comprising a screw 25 and the bracket 24 being externally supported by an arrangement comprising two screws 26. The follower 22 comprises an arm 27 which is op-

eratively associated with the cam 16, for a purpose more fully explained hereinafter.

The wiper set 11 is operatively connected to the follower 22 by an arrangement comprising an insulating bushing 28, the outer end of the wiper set 11 straddling the insulating structure 13 of the associated contact bank 12 in guided relation with respect thereto and the inner end of the wiper set 11 being secured to the insulating bushing 28. It is noted that the insulating bushing 28 is supported upon the follower 22 by a connection including a screw 29, which is so constructed and arranged that the follower 22 may be pivoted with respect to the supporting brackets 23 and 24 without effecting rotation of the insulating bushing 28. A release magnet 30 is operatively associated with the follower 22 and comprises a winding 31, a core 32 and an armature 33, the armature 33 being slidably supported on the outer end of the follower 22. More particularly, the armature 33 comprises a cylindrical body portion 34 surrounding the outer end of the follower 22 and carries an inwardly directed key 35 disposed in a longitudinally extending slot 36 formed in the follower 22, as clearly shown in Fig. 3. This connection between the armature 33 and the follower 22 permits the follower 22 to slide in the vertical direction with respect to the armature 33 without interference therewith; but securely locks the armature 33 and the follower 22 together for rotary movement, for a purpose more fully explained hereinafter. The armature 33 and consequently the follower 22 are biased in the clockwise direction, as viewed in Fig. 3, by an arrangement comprising a coil spring 37, one end of the coil spring 37 being secured to a pin 38 fixed to the cylindrical body portion 34 of the armature 33 and the other end of the coil spring 37 being fixed to an externally supported pin 39.

Two sets of switch springs S40 and S41 are operatively associated with the follower 22, the set of switch springs S40 constituting an off-normal switch and the set of switch springs S41 constituting a limit switch. More particularly, the set of switch springs S40 is operated by a pin 42 secured to the upper end of the follower 22; while the set of switch springs S41 is operated by a pin 43 carried by the insulating bushing 28.

Further the mechanism 10 comprises a motor drive including a rotatably mounted operating shaft 44 which is driven at a substantially uniform speed by an external source of power, not shown. Preferably, the operating shaft 44 is driven by a constant speed motor of the synchronous type. The inner end of the operating shaft 44 carries a non-magnetic friction disk 45 which is operatively associated with a magnetic friction disk 46 carried by the inner end of the shaft 15. More particularly, the friction disk 46 includes a cylindrical hub 47 which is slidably mounted on the inner end of the shaft 15 by an arrangement including a pin 48 fixed to the shaft 15 and a slot 49 formed in the hub 47. This pin and slot connection between the friction disk 46 and the shaft 15 permits the friction disk 46 to be slid along the shaft 15 toward and away from the associated friction disk 45, in an obvious manner. The friction disk 46 is normally biased away from the associated friction disk 45 by an arrangement comprising a spring motor or coil spring 50 surrounding the shaft 15, one end of the coil spring 50 being secured to a pin 51 fixed to the cam 16 and the other end of the coil spring 50 being secured to a pin 52 fixed to the hub 47. More particularly, the friction disk 46 is biased by the coil

spring 50 away from the associated friction disk 45 into engagement with a number of externally supported friction shoes 53. Finally, the motor drive comprises an electromagnet 54 including a winding 55 and a core 56, the core 56 being provided with field pieces 57 disposed adjacent the friction disk 45 and forming a part of a magnetic circuit including the magnetic friction disk 46.

When the mechanism 10 is fully released the friction disk 46 is biased away from the associated constantly rotating friction disk 45 by the coil spring 50 into engagement with the friction shoes 53; and the shaft 15 is biased in a counterclockwise direction, as viewed in Fig. 1, by the coil spring 20, whereby the cam 16 occupies its normal position illustrated. Also, the armature 33 and consequently the follower 22 are biased in the clockwise direction, as viewed in Fig. 3, whereby the arm 27 carried by the follower 22 cooperates with the first cam surface 17 carried by the cam 16. Also, at this time, the follower 22 occupies its fully elevated or normal position, whereby the wiper set 11 occupies its normal position disposed above the row of contact sets 14 carried by the contact bank 12. Also, when the follower 22 occupies its normal position the pin 42 carried thereby operates the set of switch springs S40 to its normal position; and the pin 43 carried by the insulating bushing 28 is disposed well above the set of switch springs S41, whereby the set of switch springs S41 is operated to its normal position.

Considering now the operation of the mechanism 10 to cause the wiper set 11 to perform a contact selecting function with respect to the associated contact bank 12, the winding 55 of the electromagnet 54 is first energized. When the winding 55 of the electromagnet 54 is thus energized, magnetic flux is set up in the core 56 and traverses a magnetic circuit, including the field pieces 57 and the magnetic friction disk 46, whereby the magnetic friction disk 46 is attracted toward the field pieces 57. More particularly, the magnetic friction disk 46 is moved against the bias of the coil spring 50 from the left toward the right, as viewed in Fig. 2, away from the friction shoes 53 and into engagement with the friction disk 45, whereby the friction disks 45 and 46 are clutched together. Accordingly, the shaft 15 is rotated in the clockwise direction, as viewed in Fig. 1, with the constantly rotating operating shaft 44 against the bias of the coil spring 20; whereby the cam 16 is rotated in the clockwise direction away from its normal position and the coil spring 20 is wound. As the cam 16 is rotated in the clockwise direction the arm 27 carried by the follower 22 follows the first cam surface 17 thereof and successively rides over the teeth 19 disposed about the periphery of the first cam surface 17, in an obvious manner. As the arm 27 carried by the follower 22 rides over the teeth 19 disposed about the periphery of the first cam surface 17 formed on the cam 16, the follower 22 is moved downwardly away from its normal position by gravity due to the general configuration of the cam 16, previously noted. More particularly, the follower 22 is moved downwardly first gradually and then abruptly repeatedly as the arm 27 rides first over the involuted surface of a tooth 19 and then over the face thereof onto the surface of the adjacent tooth. Accordingly, as the follower 22 is moved downwardly away from its normal position the insulating bushing 28 and consequently the wiper set 11 are moved downwardly

therewith. More particularly, the wiper set 11 is moved downwardly away from its normal position into successive engagement with the contact sets 14 disposed in the row in the associated contact bank 12.

After the winding 55 of the electromagnet 54 has been energized for a predetermined time interval corresponding to the desired contact set selection required by the wiper set 11, the winding 55 of the electromagnet 54 is deenergized. When the winding 55 of the electromagnet 54 is thus deenergized the magnetic flux set up in the core 56 subsides; whereby the coil spring 50 returns the magnetic friction disk 46 from the right toward the left, as viewed in Fig. 2, away from the constantly rotating friction disk 45 and into engagement with the associated friction shoes 53, whereby the friction disks 45 and 46 are declutched. When the shaft 15 is thus declutched from the operating shaft 44, the shaft 15 is rotated in the counterclockwise direction, as viewed in Fig. 1, by the wound coil spring 20. More particularly, the cam 16 carried by the shaft 15 is rotated in the counterclockwise direction back toward its normal position until the tooth 19 disposed about the periphery of the first cam surface 17 formed thereon, over which the arm 27 carried by the follower 22 last rode, engages the arm 27. When the tooth 19, over which the arm 27 last rode during the clockwise rotation of the cam 16, engages the arm 27, during the counterclockwise rotation of the cam 16, the cam 16 is locked by the arm 27 in a centered position against further rotation in the counterclockwise direction back toward its normal position. As previously noted, the arm 27 follows the first cam surface 17 formed on the cam 16 during the rotation of the cam 16 in the clockwise direction; also, the arm 27 follows the first cam surface 17 formed on the cam 16 during the rotation of the cam 16 in the counterclockwise direction back toward its normal position to its centered position. Accordingly, when the cam 16 is arrested in its centered position the follower 22 occupies a corresponding centered position; and the wiper set 11 carried by the follower 22 occupies a centered position with respect to the one of the contact sets 14 last engaged thereby in the associated contact bank 12. The rotation of the cam 16 in the counterclockwise direction following the rotation thereof in the clockwise direction, in order to effect a centering of the cam 16, positively effects a centering of the follower 22 and consequently the wiper set 11 with respect to the last engaged one of the contact sets 14 in the associated contact bank 12.

In view of the foregoing explanation of the mode of operation of the mechanism 10 to effect a selecting operation by the wiper set 11 with respect to the contact sets 14 in the associated contact bank 12, it will be understood that the winding 55 of the electromagnet 54 is energized for a variable time interval corresponding to the desired contact set 14 in the contact bank 12 which is to be selected by the wiper set 11, and that during this time interval the wiper set 11 is moved downwardly away from its normal position slightly past the desired contact set 14 in the associated contact bank 12; and at the conclusion of the time interval mentioned the wiper set 11 is then moved upwardly back toward its normal position to a centered position with respect to the selected contact set 14 in the associated contact bank 12. This arrangement for positively centering the wiper set 11 with respect to the last engaged contact set 14 in the asso-

ciated contact bank 12 minimizes the necessity for exact timing during the interval in which the winding 55 of the electromagnet 54 is energized, and renders it necessary that the timing referred to be only approximate. More particularly, it will be understood that, in the mechanism 10, the timing of the energization of the winding 55 of the electromagnet 54 may be as much as five per cent. too long or too short without causing false selection by the wiper set 11 with respect to the contact sets 14 in the associated contact bank 12. Finally, in this connection, it is noted that, in the mechanism 10, the timing of the energization of the winding 55 of the electromagnet 54 should be within the limits mentioned in order to effect proper selection by the wiper set 11 with respect to the contact sets 14 in the associated contact bank 12. At this time, the wiper set 11 is positively centered with respect to the selected contact set 14 in the associated contact bank 12 and is locked in its selecting position by the cooperation between the arm 27 carried by the follower 22 and the engaged tooth 19 disposed about the periphery of the first cam surface 17 formed on the cam 16.

In order to release the mechanism 10 and to cause the wiper set 11 to be returned upwardly to its normal position, the winding 31 of the electromagnet 30 is energized for a short time interval. When the winding 31 of the electromagnet 30 is thus energized, magnetic flux is set up in the core 32, whereby the armature 33 is attracted. When the armature 33 is thus attracted it is rotated in the counterclockwise direction, as viewed in Fig. 3, against the bias of the coil spring 37, whereby the follower 22 is pivoted in the supporting brackets 23 and 24 in the counterclockwise direction. When the follower 22 is thus pivoted in the counterclockwise direction the arm 27 carried thereby is moved out of engagement with the associated tooth 19 disposed on the periphery of the first cam surface 17 formed on the cam 16 and into engagement with the second cam surface 18 formed on the cam 16, as clearly indicated in Fig. 2; whereby the cam 16 is unlocked and rotated in the counterclockwise direction by the coil spring 20 back into its normal position. When the cam 16 is thus rotated in the counterclockwise direction back into its normal position the arm 27 follows the smooth second cam surface 18 formed thereon, whereby the follower 22 is elevated and returned to its normal position. When the follower 22 is thus elevated and returned to its normal position the wiper set 11 carried thereby is thus elevated and returned to its normal position with respect to the contact sets 14 in the associated contact bank 12.

Subsequently, the winding 31 of the electromagnet 30 is deenergized, whereby the armature 33 is rotated in the clockwise direction, as viewed in Fig. 3, by the coil spring 37. When the armature 33 is thus rotated in the clockwise direction the follower 22 is pivoted in the supporting brackets 23 and 24 in a clockwise direction; whereby the arm 27 disengages the second cam surface 18 formed on the cam 16 and reengages the first cam surface 17 formed on the cam 16, the first cam surface 17 and the second cam surface 18 formed on the cam 16 being contiguous and flush when the cam 16 occupies its normal position. At this time, the mechanism 10 is completely released.

In conjunction with the operation of the

mechanism 10, it is pointed out that the set of switch springs S40 is operated from its normal position to its off-normal position when the pin 42 carried by the follower 22 is lowered due to operation of the follower 22 away from its normal position; on the other hand, the set of switch springs S40 is operated from its off-normal position back to its normal position by the pin 42 carried by the follower 22 when the follower 22 is elevated and returned to its normal position. Finally, the set of switch springs S41 is operated from its normal position to its off-normal position by the pin 43 carried by the insulating bushing 28 in the event the follower 22 is lowered away from its normal position an amount sufficient to cause the wiper set 11 to disengage the last contact set 14 in the associated contact bank 12; on the other hand, the set of switch springs S41 is operated from its off-normal position back to its normal position when the pin 43 carried by the insulating bushing 28 is elevated due to the elevation of the follower 22 back into its normal position. Finally, it is noted that, in the event the set of switch springs S41 is operated to its off-normal position, circuit control means is governed to deenergize the winding 55 of the electromagnet 54 and to energize the winding 31 of the electromagnet 30, whereby the mechanism 10 is released, in the manner explained above.

Referring now more particularly to Figs. 4 and 5 of the drawings, there is illustrated a modified form of the switching mechanism 110 embodying the present invention and comprising a wiper set 111 and an associated contact bank 112, the contact bank 112 including an insulating structure 113 supporting a plurality of vertically spaced-apart contact sets 114 arranged in a row. Also, the mechanism 110 comprises a rotatably mounted shaft 115 having a ratchet wheel 116 and a gear 117 rigidly secured thereto. The ratchet wheel 116 has a plurality of spaced-apart teeth 119 disposed about the periphery thereof. The ratchet wheel 116 and the gear 117 are biased in the counterclockwise direction into normal positions, illustrated in Fig. 5, by an arrangement comprising a surrounding coil spring 120, one end of the coil spring 120 being secured to the gear 117 and the other end of the coil spring 120 being secured to an externally supported pin 121. The gear 117 cooperates with a rack 122 which is mounted by two brackets 123 and 124 for sliding movement, the bracket 123 being externally supported by an arrangement comprising two screws 125 and the bracket 124 being externally supported by an arrangement comprising two screws 126.

The wiper set 111 is operatively connected to the rack 122 by an arrangement comprising an insulating bushing 128, the outer end of the wiper set 111 straddling the insulating structure 113 of the associated contact bank 112 in guided relation with respect thereto and the inner end of the wiper set 111 being secured to the insulating bushing 128. It is noted that the insulating bushing 128 is secured to the lower end of the rack 122 by a connection including a screw 129. An electromagnet 130, constituting a release magnet, is operatively associated with the ratchet wheel 116 and comprises a winding 131, a core 132 and an armature 134 mounted upon an externally supported pivot pin 135. The armature 134 carries an outwardly and upwardly projecting arm 136 constituting a pawl cooperating with the teeth 119 disposed about the

periphery of the ratchet wheel 116. The armature 134 and consequently the pawl 136 are biased in the clockwise direction, as viewed in Fig. 5, by an arrangement comprising a coil spring 137; one end of the coil spring 137 being secured to a pin 138 fixed to the outer end of the armature 134 and the other end of the coil spring 137 being fixed to an externally supported pin 139.

Two sets of switch springs S140 and S141 are operatively associated respectively with the ratchet wheel 116 and the rack 122, the set of switch springs S140 constituting an off-normal switch and the set of switch springs S141 constituting a limit switch. More particularly, the set of switch springs S140 is operated by a pin 142 fixed to the side wall of the ratchet wheel 116; while the set of switch springs S141 is operated by a pin 143 carried on the lower end of the rack 122.

Further, the mechanism 110 comprises a motor drive, including a rotatably mounted operating shaft 144, which is driven at a substantially uniform speed by an external source of power, not shown. Preferably, the operating shaft 144 is driven by a constant speed motor of the synchronous type. The inner end of the operating shaft 144 carries a nonmagnetic friction disk 145 which is operatively associated with a magnetic friction disk 146 carried by the inner end of the shaft 115. More particularly, the friction disk 146 includes a cylindrical hub 147 which is slidably mounted on the inner end of the shaft 115 by an arrangement including a pin 148 fixed to the shaft 115 and a slot 149 formed in the hub 147. This pin and slot connection between the friction disk 146 and the shaft 115 permits the friction disk 146 to be slid along the shaft 115 toward and away from the associated friction disk 145, in an obvious manner. The friction disk 146 is normally biased away from the associated friction disk 145 by an arrangement comprising a spring motor or coil spring 150 surrounding the shaft 115, one end of the coil spring 150 being secured to a pin 151 fixed to the ratchet wheel 116 and the other end of the coil spring 150 being secured to a pin 152 fixed to the hub 147. More particularly, the friction disk 146 is biased by the coil spring 150 away from the associated friction disk 145 into engagement with a number of externally supported friction shoes 153. Finally, the motor drive comprises an electromagnet 154 including a winding 155 and a core 156, the core 156 being provided with field pieces 157 disposed adjacent the friction disk 145 and forming a part of a magnetic circuit, including the magnetic friction disk 146.

When the mechanism 110 is fully released the friction disk 146 is biased away from the associated constantly rotating friction disk 145 by the coil spring 150 into engagement with the friction shoes 153; and the shaft 115 is biased in the counterclockwise direction, as viewed in Fig. 5, by the coil spring 122, whereby the ratchet wheel 116 and the gear 117 occupy their normal positions illustrated. When the gear 117 occupies its normal position the rack 122 occupies its fully elevated or normal position, whereby the wiper set 111 occupies its normal position disposed above the row of contact sets 114 carried by the contact bank 112. Also, the armature 134 and consequently the pawl 136 are biased in the clockwise direction about the pivot pin 135, as viewed in Fig. 5, by the coil spring 137; whereby the pawl 136 engages one of the teeth 119 disposed on the periphery of the ratchet wheel 116 in order

positively to lock the ratchet wheel 116 in its normal position. Further, when the ratchet wheel 116 occupies its normal position the pin 142 carried thereby operates the set of switch springs S140 to its normal position; and when the rack 122 occupies its normal position the pin 143 carried on the lower end thereof is disposed well above the set of switch springs S141, whereby the set of switch springs S141 is operated to its normal position.

Considering now the operation of the mechanism 110 to cause the wiper set 111 to perform a contact selecting function with respect to the associated contact bank 112, the winding 155 of the electromagnet 154 is first energized. When the winding 155 of the electromagnet 154 is thus energized, magnetic flux is set up in the core 156 and traverses a magnetic circuit including the field pieces 157 and the magnetic friction disk 146, whereby the magnetic friction disk 146 is attracted toward the field pieces 157. More particularly, the magnetic friction disk 146 is moved against the bias of the coil spring 150 from the right toward the left, as viewed in Fig. 4, away from the friction shoes 153 and into engagement with the friction disk 145; whereby the friction disks 145 and 146 are clutched together. Accordingly, the shaft 115 is rotated in the clockwise direction, as viewed in Fig. 5, with the constantly rotating operating shaft 144 against the bias of the coil spring 120; whereby the ratchet wheel 116 and the gear 117 are rotated in the clockwise direction away from their normal positions and the coil spring 120 is wound. As the gear 117 is rotated in the clockwise direction the rack 122 is driven at a substantially constant speed downwardly away from its normal position. Accordingly, as the rack 122 is moved downwardly away from its normal position the insulating bushing 128 and consequently the wiper set 111 are moved downwardly therewith. More particularly, the wiper set 111 is moved downwardly away from its normal position into successive engagement with the contact sets 114 disposed in the row in the associated contact bank 112. Also, as the ratchet wheel 116 is rotated in the clockwise direction the pawl 136 rides over the teeth 119 disposed about the periphery thereof.

After the winding 155 of the electromagnet 154 has been energized for a predetermined time interval corresponding to the desired contact set selection required by the wiper set 111, the winding 155 of the electromagnet 154 is deenergized. When the winding 155 of the electromagnet 154 is thus deenergized the magnetic flux set up in the core 156 subsides; whereby the coil spring 150 returns the magnetic friction disk 146 from the left toward the right, as viewed in Fig. 4, away from the constantly rotating friction disk 145 and into engagement with the associated friction shoes 153, whereby the friction disks 145 and 146 are declutched. When the shaft 115 is thus declutched from the operating shaft 144, it is rotated in the counterclockwise direction, as viewed in Fig. 5, by the wound coil spring 120. More particularly, the ratchet wheel 116 carried by the shaft 115 is rotated in the counterclockwise direction back toward its normal position until the tooth 119 disposed about the periphery thereof, over which the pawl 136 last rode, engages the pawl 136 mentioned. When the tooth 119, over which the pawl 136 last rode during the clockwise rotation of the ratchet wheel 116, engages the pawl 136 during the counterclockwise

rotation of the ratchet wheel 116, the ratchet wheel 116 is locked by the pawl 136 in a centered position against further rotation in the counterclockwise direction back toward its normal position. As previously noted, the rack 122 is driven downwardly away from its normal position by the gear 117 during the rotation of the ratchet wheel 116 in the clockwise direction; also the rack 122 is driven upwardly back toward its normal position by the gear 117 during the rotation of the ratchet wheel 116 in the counterclockwise direction back toward its normal position to its centered position.

Accordingly, when the ratchet wheel 116 is arrested in its centered position the rack 122 occupies a corresponding centered position; and the wiper set 111 carried by the rack 122 occupies a centered position with respect to the one of the contact sets 114 last engaged thereby in the associated contact bank 112. The rotation of the ratchet wheel 116 in the counterclockwise direction, following the rotation thereof in the clockwise direction, in order to effect a centering of the ratchet wheel 116, positively effects a centering of the rack 122 and consequently the wiper set 111 with respect to the last engaged one of the contact sets 114 in the associated contact bank 112.

In view of the foregoing explanation of the mode of operation of the mechanism 110 to effect a selecting operation by the wiper set 111 with respect to the contact sets 114 in the associated contact bank 112, it will be understood that the winding 155 of the electromagnet 154 is energized for a variable time interval corresponding to the desired contact set 114 in the contact bank 112 which is to be selected by the wiper set 111; and that, during this time interval, the wiper set 111 is moved downwardly away from its normal position slightly past the desired contact set 114 in the associated contact bank 112; and, at the conclusion of the time interval mentioned, the wiper set 111 is then moved upwardly back toward its normal position to a centered position with respect to the selected contact set 114 in the associated contact bank 112. This arrangement for positively centering the wiper set 111 with respect to the last engaged contact set 114 in the associated contact bank 112 minimizes the necessity for exact timing during the interval in which the winding 155 of the electromagnet 154 is energized; and renders it necessary that the timing referred to be only approximate. More particularly, it will be understood that in the mechanism 110 the timing of the energization of the winding 155 of the electromagnet 154 may be as much as five per cent. too long or too short without causing false selection by the wiper set 111 with respect to the contact sets 114 in the associated contact bank 112. Finally, in this connection, it is noted that in the mechanism 110 the timing of the energization of the winding 155 of the electromagnet 154 should be within the limits mentioned in order to effect proper selection by the wiper set 111 with respect to the contact sets 114 in the associated contact bank 112.

At this time, the wiper set 111 is positively centered with respect to the selected contact set 114 in the associated contact bank 112 and is locked in its selected position by the cooperation between the pawl 136 carried by the armature 134 and the engaged tooth 119 disposed on the periphery of the ratchet wheel 116.

In order to release the mechanism 110 and to cause the wiper set 111 to be returned upwardly

to its normal position, the winding 131 of the electromagnet 130 is energized for a short time interval. When the winding 131 of the electromagnet 130 is thus energized, magnetic flux is set up in the core 132, whereby the armature 134 is attracted. When the armature 134 is thus attracted it is rotated in the counterclockwise direction about the pivot pin 135, as viewed in Fig. 5, against the bias of the coil spring 137, whereby the pawl 136 is moved out of engagement with the associated tooth 119 disposed on the periphery of the ratchet wheel 116, whereby the ratchet wheel 116 is unlocked and rotated in the counterclockwise direction by the coil spring 120 back into its normal position. When the ratchet wheel 116 is thus rotated in the counterclockwise direction back into its normal position the gear 117 drives the rack 122 upwardly back to its normal position. When the rack 122 is thus elevated and returned to its normal position the wiper set 111 carried thereby is thus elevated and returned to its normal position with respect to the contact sets 114 in the associated contact bank 112. Subsequently, the winding 131 of the electromagnet 130 is deenergized, whereby the armature 134 is rotated in the clockwise direction about the pivot pin 135, as viewed in Fig. 5, by the coil spring 137. When the armature 134 is thus rotated in the clockwise direction the pawl 136 reengages the associated tooth 119 disposed on the periphery of the ratchet wheel 116. At this time, the mechanism 110 is completely released.

In conjunction with the operation of the mechanism 110, it is pointed out that the set of switch springs S140 is operated from its normal position to its off-normal position when the pin 142 carried by the ratchet wheel 116 is moved in the clockwise direction as the rack 122 is lowered away from its normal position; on the other hand, the set of switch springs S140 is operated away from its off-normal position back to its normal position by the pin 142 carried by the ratchet wheel 116 when the ratchet wheel 116 is rotated in the counterclockwise direction as the rack 122 is elevated and returned to its normal position. Finally, the set of switch springs S141 is operated from its normal position to its off-normal position by the pin 143 carried on the lower end of the rack 122 in the event the rack 122 is lowered away from its normal position an amount sufficient to cause the wiper set 111 to disengage the last contact set 114 in the associated contact bank 112; on the other hand, the set of switch springs S141 is operated from its off-normal position back to its normal position when the pin 143 carried by the rack 122 is elevated and returned to its normal position. Finally, it is noted that, in the event the set of switch springs S140 is operated to its off-normal position, circuit control means is governed to deenergize the winding 155 of the electromagnet 154 and to energize the winding 131 of the electromagnet 130, whereby the mechanism 110 is released in the manner explained above.

Referring now more particularly to Fig. 6 of the drawings, there is diagrammatically illustrated an automatic telephone system embodying the present invention and incorporating switching mechanism of either the form shown in Figs. 1 to 3, inclusive, or the form shown in Figs. 4 and 5. In the description of the circuit shown in Fig. 6, the reference numbers used in describing the form of switching mechanism illustrated in Figs. 1 to 3, inclusive, have been used, as far as possible, but it will be readily apparent that the corre-

sponding reference numerals used in the description of the form of construction shown in Figs. 4 and 5 may be substituted therefor. The telephone system illustrated comprises a telephone station 600 having a telephone line 605 extending thereto, a selector 610 terminating the telephone line 605, and ten telephone lines, including the telephone line 685, accessible to the selector 610. The telephone station 600 comprises station equipment including a call transmitter 601 of the construction and arrangement of that disclosed in Figs. 1 and 2 of the previously mentioned Willis patent, a hook switch 602, and a telephone instrument, not shown. The selector 610 comprises a switching mechanism 10 which may be of either of the two forms described above, which includes a go magnet 54, a release magnet 30 and a wiper set provided with the wipers 691 and 692. Also associated with the switching mechanism 10 are two sets of off-normal switch springs S694 and S695 and a set of limit switch springs S696. Also, the selector 610 comprises a relay group, including a switch-through relay R620, a line relay R630, a hold relay R640, a release relay R650 and two control relays R660 and R670, and a control network connected and arranged in a manner more fully explained hereinafter. Finally, each of the telephone lines 685, etc., is provided with a line circuit including a seizure relay, the telephone line 685 being provided with a line circuit including the seizure relay R680. A better understanding of the connection and arrangement of the telephone system will be facilitated from a consideration of the following description of the mode of operation of the apparatus incorporated therein incident to the extension of a connection from the telephone station 600 to a called one of the telephone lines 685, etc.

Considering now the extension of a call from the telephone station 600, the operator thereat first removes the receiver of the telephone instrument from its associated switchhook; whereby the hook switch 602 is operated to complete a loop circuit for energizing in series the upper and lower windings of the line relay R630 in the selector 610. The last-mentioned loop circuit extends from ground by way of the lower winding of R630, the contacts 624, one of the line conductors of the telephone line 605, the hook switch 602 and the call transmitter 601 at the telephone station 600, the other line conductor of the telephone line 605, the contacts 622, and the upper winding of R630 to battery. When thus energized the line relay R630 operates to complete, at the contacts 632, an obvious circuit, including the contacts 661 and 621, for energizing the winding of the hold relay R640, thereby to cause the latter relay to operate. At this time, the selector 610 is rendered responsive to a digit in the form of a single impulse of variable time duration transmitted thereto over the telephone line 605 from the telephone station 600 to select a corresponding one of the telephone lines 685, etc.

Now assuming that the operator at the telephone station 600 operates the call transmitter 601 in accordance with a given digit having an open-circuit period corresponding to the called telephone line 685, the call transmitter 601 first interrupts the previously traced loop circuit for energizing in series the upper and lower windings of the line relay R630 and, at the conclusion of the previously mentioned time interval, completes the loop circuit mentioned. Accordingly, the line relay R630 restores and then, at the conclusion of the predetermined time interval

mentioned, reoperates. Upon restoring, the line relay **R630** completes, at the contacts **631**, an obvious circuit, including the contacts **661**, **621** and **641**, for energizing the go magnet **54**, thereby to cause the latter magnet to operate and initiate operation of the switching mechanism **10**, in the manner previously explained. More particularly, the wiper set of the switching mechanism **10** is moved at a substantially constant speed over the contact sets in the associated contact bank terminating the telephone lines **685**, etc., in the manner previously explained. When operation of the switching mechanism **10** is thus initiated the sets of off-normal switch springs **S694** and **S695** are operated. When the set of off-normal switch springs **S694** is thus operated an obvious holding circuit, including the contacts **661**, **621** and **631**, is completed for energizing the go magnet **54**; and when the set of off-normal switch springs **S695** is thus operated a circuit traced hereinafter 20 is prepared for energizing the winding of the switch-through relay **R620**.

Subsequently, when the line relay **R630** reoperates it interrupts, at the contacts **631**, the previously traced holding circuit for energizing the go magnet **54**, thereby to cause the latter magnet to restore in order to arrest further operation of the switching mechanism **10**. The wiper set of the switching mechanism **10** is then positively centered with respect to the contact set in the associated contact bank terminating the called telephone line **685**, in the manner previously explained. Also, upon operating, the line relay **R630** recompletes, at the contacts **632**, the previously traced circuit for energizing the winding of the hold relay **R640**, thereby to cause the latter relay to reoperate in the event it restored during the transmission of the digit from the telephone station **600**, the hold relay **R640** being of the slow-to-release type. Further, the line relay **R630** completes, at the contacts **633**, the previously mentioned circuit, including the contacts **627** and **663** and the set of off-normal switch springs **S695**, for energizing the winding of the switch-through relay **R620**. When thus energized the switch-through relay **R620** operates to complete, at the contacts **628**, an obvious holding circuit substantially identical to that previously traced for energizing the winding thereof. Further, the switch-through relay **R620** interrupts, at the contacts **621**, the previously traced circuit for energizing the winding of the hold relay **R640**, thereby to cause the latter relay to restore shortly thereafter. Also, the switch-through relay **R620** 50 interrupts, at the contacts **622** and **624**, the previously traced circuit for energizing in series the upper and lower windings of the line relay **R630**, thereby to cause the latter relay to restore. Finally, the switch-through relay **R620** completes, at the contacts **623** and **625**, a loop circuit for energizing in series the upper and lower windings of the seizure relay **R680** in the line circuit associated with the called telephone line **685**. The last-mentioned loop circuit extends from ground by way of the lower winding of **R630**, the wiper **692** of the switching mechanism **10**, and the contacts **625** to one of the line conductors of the telephone line **605**; and from battery by way of the upper winding of **R630**, the wiper **691** of the switching mechanism **10** and the contacts **623** to the other line conductor of the telephone line **605**, the line conductors of the telephone line **605** being connected together by way of the bridge at the telephone station **600**, previously mentioned. When this loop circuit is

completed the seizure relay **R680** is energized and operates.

Upon operating, the seizure relay **R680** completes, at the contacts **682**, an obvious circuit for energizing the winding of the control relay **R670**, thereby to cause the latter relay to operate. Upon operating, the control relay **R670** completes, at the contacts **672**, an obvious multiple holding circuit for energizing the winding of the switch-through relay **R620**, thereby to retain the latter relay in its operated position. Also the control relay **R670** completes, at the contacts **671**, an obvious circuit for energizing the winding of the control relay **R660**, thereby to cause the latter relay to operate. Upon operating, the control relay **R660** interrupts, at the contacts **661**, a further point in the previously traced circuits for energizing the winding of the hold relay **R640** and the go magnet **54**; interrupts, at the contacts **663**, a point in the original holding circuit for energizing the winding of the switch-through relay **R620**; and prepares, at the contacts **662**, a point in an obvious circuit for energizing the winding of the release relay **R650**.

Also, when the seizure relay **R680** operates it interrupts, at the contacts **681**, an obvious bridge connection between the line conductors of the called telephone line **685**, whereby the calling telephone line **605** is operatively connected to the called telephone line **685** for telephone communication thereover. More particularly, the line conductors of the telephone line **685** are respectively connected by way of the condensers **683** and **684** to the previously traced loop circuit extending between the telephone station **600** and the seizure relay **R680**. Also it is noted that, in the event it is necessary to perform further switching operations over the called telephone line **685**, this may be accomplished by the seizure relay **R680** under the control of the call transmitter **601** at the telephone station **600**. More particularly, in the event the call transmitter **601** is reoperated in accordance with an additional digit, the seizure relay **R680** first restores and then reoperates at the conclusion of the digit mentioned. Upon restoring, the seizure relay **R680** recompletes, at the contacts **681** the previously mentioned bridge connection between the line conductors of the called telephone line **685**. Subsequently, when the seizure relay **R680** reoperates it interrupts, at the contacts **681**, the previously mentioned bridge connection between the line conductors of the called telephone line **685**. Accordingly, the call transmitter **601** at the telephone station **600** is operative to transmit additional digits in the form of single impulses of variable time duration over the called telephone line **685** by way of the telephone line **605** and the selector **610**, in the event this is necessary. Also, in this connection, it is pointed out that, during the transmission of the additional digits from the call transmitter **601** at the telephone station **600** over the called telephone line **685**, the seizure relay **R680** occupies its restored position, whereby the previously traced circuit for energizing the winding of the control relay **R670** is interrupted during the time interval mentioned. However, the control relay **R670** is 60 of the slow-to-release type and has a release characteristic such that the latter relay does not restore during impulsive. Accordingly, at this time, an operative connection is completed between the telephone station **600** and the called telephone line **685**, including the telephone line

605 and the selector 610, for telephone communication purposes.

The release of the established connection is under the control of the operator at the telephone station 600 and is effected when he replaces the receiver of the telephone instrument thereat upon its associated switch-hook in order to operate the hook switch 602, in an obvious manner. When the hook switch 602 is thus operated the previously traced loop circuit for energizing in series the upper and lower windings of the seizure relay R680 is interrupted, thereby to cause the latter relay to restore. Upon restoring, the seizure relay R680 recompletes, at the contacts 681, the previously mentioned bridge connection between the line conductors of the telephone line 685; and interrupts, at the contacts 682, the previously mentioned circuit for energizing the winding of the control relay R670, thereby to cause the latter relay to restore shortly thereafter, the control relay R670 being of the slow-to-release type, as previously noted. Upon restoring, the control relay R670 interrupts, at the contacts 672, the previously traced alternative holding circuit for energizing the winding of the switch-through relay R620, thereby to cause the latter relay to restore. Also the control relay R670 interrupts, at the contacts 671, the previously mentioned circuit for energizing the winding of the control relay R660; however, the latter relay does not restore immediately as it is of the slow-to-release type.

Upon restoring, the switch-through relay R620 reprepares, at the contacts 621, the previously traced circuit for energizing the winding of the hold relay R640; interrupts, at the contacts 628, a further point in the holding circuit for energizing the winding thereof; interrupts, at the contacts 623 and 625, a further point in the previously traced loop circuit for energizing in series the upper and lower windings of the seizure relay R680; and prepares, at the contacts 622 and 624, a point in the previously traced loop circuit for energizing in series the upper and lower windings of the line relay R630. Finally, the switch-through relay R620 completes, at the contacts 626, the previously mentioned circuit for energizing the winding of the release relay R650, thereby to cause the latter relay to operate. Upon operating, the release relay R650 completes, at the contacts 651, an obvious circuit for energizing the release magnet 30, thereby to cause the latter magnet to operate. Upon operating, the release magnet 30 unlocks the wiper set of the switching mechanism 10, whereby the switching mechanism 10 is mechanically released by the associated spring motor, in the manner previously explained. When the switching mechanism 10 is thus fully released the sets of off-normal springs S694 and S695 are operated back to their normal positions. Shortly after the switching mechanism 10 is thus released the control relay R660 restores, as previously noted. Upon restoring, the control relay R660 interrupts, at the contacts 662, the previously mentioned circuit for energizing the winding of the release relay R650, thereby to cause the latter relay to restore shortly thereafter, the release relay R650 being of the slow-to-release type. Upon restoring, the release relay R650 interrupts, at the contacts 651, the previously mentioned circuit for energizing the release magnet 30, thereby to cause the latter magnet to restore, whereupon the switching mechanism 10 is reconditioned for further operation. At this time, the selector 610 is complete-

ly released and all of the apparatus utilized in establishing the connection between the telephone station 600 and the called telephone line 685 are completely released and available for further use.

In conjunction with the operation of the selector 610 and the switching mechanism 10 incorporated therein, it is pointed out that, should the operator at the telephone station 600 remove the receiver of the telephone instrument thereat from its associated switchhook and then replace the receiver upon its associated switchhook without operating the call transmitter 601, thereby abandoning the call, the selector 610 would be seized and operation of the switching mechanism 10 incorporated therein would be initiated, in the manner previously explained. However, in this event, the line relay R630 remains restored for an indefinite time interval, whereby the wiper set of the switching mechanism 10 is driven beyond the last contact set in the associated contact bank. When the wiper set of the switching mechanism 10 is thus driven beyond the last contact set in the associated contact bank the set of limit switch springs S696 is operated. More particularly, the set of limit switch springs S696 is operated to complete, at the contacts 697, and then to interrupt, at the contacts 698, an obvious path for applying ground potential to the control conductor C693 and consequently the circuit for energizing the winding of the control relay R670. Accordingly, the control relay R670 operates and then subsequently restores, thereby to effect operation of the control relay R660, in the manner previously explained. Upon operating, the control relay R660 interrupts, at the contacts 661, the previously traced holding circuit for energizing the go magnet 54, thereby positively to arrest further movement of the wiper set of the switching mechanism 10 with respect to the associated contact bank. Also the control relay R660 completes, at the contacts 662, the previously traced circuit for energizing the winding of the release relay R650, thereby to cause the latter relay to operate. Subsequently, when the control relay R670 restores it effects restoration of the control relay R660 and the release relay R650. While the release relay R650 occupied its operated position the release magnet 30 was operated, thereby to effect the release of the switching mechanism 10, in the manner previously explained. Incident to the restoration of the release relay R650 the release magnet 30 is released, thereby to condition the switching mechanism 10 for further operation, in the manner previously explained. At this time, the selector 610 and the switching mechanism 10 incorporated therein are completely released and available for further use.

While one embodiment of the invention has been disclosed, it will be understood that various modifications may be made therein which are within the true spirit and scope of the invention.

What is claimed is:

1. In a switching system wherein a single variable digit is transmitted over a line by a timing transmitter, switching mechanism comprising a wiper having a normal position, a plurality of spaced-apart contacts disposed in a row and accessible to said wiper, means controlled during the receipt of said single digit over said line for continuously advancing said wiper away from its normal position along said row into successive engagement with said contacts, means controlled at the conclusion of the transmission of said single

digit over said line for centering said wiper with respect to the one of said contacts last engaged thereby, and means controlled in response to the disengagement by said wiper of the last one of said contacts in said row for returning said wiper to its normal position.

2. In a switching system wherein a timing transmitter is selectively operable to alter the circuit condition of a line and to maintain said altered circuit condition during different time intervals, switching mechanism comprising a wiper having a normal position, a plurality of spaced-apart contacts disposed in a row and accessible to said wiper, means controllable over said line for continuously advancing said wiper at a substantially uniform speed away from its normal position along said row into successive engagement with said contacts during the time interval through which said altered circuit condition of said line is maintained, means controlled at the conclusion of said altered circuit condition of said line for returning said wiper toward its normal position and to a centered position with respect to the one of said contacts last engaged thereby, and means controlled in response to the disengagement by said wiper of the last one of said contacts in said row for returning said wiper to its normal position.

3. Switching mechanism comprising a cam having a normal position, a follower arranged to ride upon a cam surface of said cam, motor means adapted to advance said cam continuously away from its normal position, said cam surface having means whereby said cam may be definitely located in one of a plurality of spaced-apart positions by said follower upon reverse movement of said cam toward said normal position, means for selectively controlling said motor means to determine the extent of said advance of said cam from said normal position, means operated when the advancement of said cam away from said normal position is arrested for returning said cam toward said normal position and thereby causing it to be located in one of said positions by said follower, and contact selecting means operatively connected to said follower.

4. Switching mechanism comprising a cam having a normal position and carrying a plurality of spaced-apart teeth disposed about the cam surface thereof, a follower adapted to ride upon the cam surface of said cam, motor means adapted to advance said cam continuously away from its normal position, means for selectively controlling said motor means, means governed when the advancement of said cam away from its normal position by said motor means is arrested for returning said cam toward its normal position to the nearest one of a plurality of spaced-apart centered positions, said one centered position being established when said follower is engaged by the one of the teeth disposed about the cam surface of said cam which was last to ride under said

cam, and contact selecting means operatively connected to said follower.

5. Switching mechanism comprising a cam having a normal position, said cam including a first cam surface carrying a plurality of spaced-apart teeth and a second smooth cam surface, a follower normally associated with said first cam surface and adapted to be associated with said second cam surface, motor means adapted to advance said cam continuously away from its normal position, means for selectively controlling said motor means, means governed when the advancement of said cam away from its normal position by said motor means is arrested for returning said cam toward its normal position, means governed when the one of the teeth carried by said first cam surface which was last to ride under said follower engages said follower for arresting the return of said cam toward its normal position, thereby to establish a corresponding centered position for said cam, means for disassociating said follower from said first cam surface and for associating it with said second cam surface, means governed when said follower is disassociated from said first cam surface for returning said cam to its normal position, and contact selecting means operatively connected to said follower.

6. The combination in switching mechanism of a rotatable toothed member having a normal position, a follower mounted for linear movement and having a part arranged to ride continuously upon said toothed member, a plurality of spaced-apart contacts disposed in a row, a wiper carried by said follower and adapted to engage said contacts successively upon endwise movement of said follower, motor means adapted to rotate said toothed member from its normal position to advance said wiper over said contacts, a spring adapted to be wound by said rotation of said toothed member, means for controlling said motor means, and means including said spring and operative when the operation of said motor means is arrested for returning said wiper and said toothed member to their normal positions.

45 7. The combination in switching mechanism of a rotatable cam having a peripheral surface including a toothed part and a smooth part, a follower having a part adapted to ride normally on said toothed part of said cam, a plurality of contacts arranged in a row, a wiper carried by said follower for movement over said contacts, motor means for rotating said cam in one direction with said follower riding on said toothed part, a spring adapted to be wound by said rotation of said cam, means for controlling the operation of said motor means, and means actuated when said motor means is arrested for moving said part of said follower into engagement with said smooth part of said cam and thereby permitting said spring to return to its normal position.

BERNARD D. WILLIS.
